UNITED STATES PATENT OFFICE.

DAVID P. MORAN, OF WICHITA, KANSAS.

CAR-COUPLING.

SPECIFICATION forming part of Letters Patent No. 748,874, dated January 5, 1904.

Application filed March 13, 1903. Serial No. 147,581. (No model.)

To all whom it may concern:

Be it known that I, DAVID P. MORAN, a citizen of the United States, residing at the city of Wichita, in the State of Kansas, have invented a certain new and useful Car-Coupling, of which the following is such a full, clear, and exact description as will enable any one skilled in the art to which it appertains to make and use the same, reference being had to the accompanying drawings, forming part of this specification.

My invention relates to a car-coupling, and more particularly to that class of car-couplings usually known as the "Janney" type, and consists of a pair of coupler-heads, each provided with a pivoted knuckle, and means for locking the knuckles in engagement with each other.

One object of my invention is to provide means for preventing one of the coupling-heads from falling down upon the track when it is broken off or pulled out, thus endangering the remaining cars of the train.

Another object of my invention is to provide means for rigidly coupling the heads together when one or both of the knuckles have become disabled.

My invention consists in part in the combination, with a draw-head and pivoted knuckle, of a forwardly-projecting stop rigidly carried by the upper face of said knuckle, said stop being elevated above the upper face of the coupler, whereby vertical play is permitted between the said coupler and a second coupler with which it co-operates.

My invention also consists in various other novel features and details of construction, all of which will be described in the following specification and pointed out in the claims affixed thereto.

In the accompanying drawings, which illustrate a pair of co-operating coupling devices provided with attachments made in accordance with my invention, Figure 1 is a top plan view. Fig. 2 is a horizontal section showing the manner of coupling the two heads together when one of the knuckles is disabled. Fig. 3 is a view similar to Fig. 2, but showing the manner of coupling the heads together when both knuckles are disabled; and Fig. 4 is a side elevation showing the position

assumed by the parts when one of the heads is broken off or pulled out.

Like marks of reference refer to similar parts in the several views of the drawings. 55

10 represents the draw-bars, each of which is provided with a coupling-head 11 of any usual form. Each of the coupling-heads 11 is provided with a knuckle 12. The knuckles 12 are pivoted in position by means of the usual 60 knuckle-pins 14, passing through eyes 15 on the heads 11. Each of the knuckles 12 is provided with a rearwardly-extending frame 16, which is held by means of a pin 17 or any of the usual and well-known devices, so as to 65 lock the knuckles in engagement. In order to prevent one of the draw-heads from falling upon the track when it becomes broken off or pulled out, I provide each of the knuckles 12 with a forwardly-projecting stop 18, which 70 stop is formed integral with the upper face of the knuckle 12 at a point intermediate of its length. The stops 18 are elevated above the faces of the draw-heads by means of standards or stems 19, Figs. 4 and 6. By 75 thus raising the stops 18 above the faces of the draw-heads vertical play is allowed between the two draw-heads, and two cars can be coupled together when their draw-heads are not exactly upon the same level, as often 80 happens in practice. In case one of the draw-heads breaks off or is pulled out from the car carrying it it will drop down, as shown at the right hand of Fig. 4, until its stop 18 comes in contact with the upper face of the 85 draw-head 11 of the opposite car. This will prevent further movement of the draw-head, and the weight of the rear end of the draw-head will cause the two draw-heads to be clamped, owing to the inclined position taken 90 by the broken head, and thus a considerable proportion of the weight of the head will be taken off the stop 18, and hence this stop will not be liable to become broken off, so as to allow the head to drop. In order to provide 95 means for rigidly coupling the heads together when one or both of the knuckles 12 have become disabled, I provide a pair of rigid coupling-bars of different length 20 and 21. In case only one of the knuckles becomes disabled the short bar 20 is used, as shown in Fig. 2, one end of the said bar 20 being se- 100

cured to the knuckle 12 by means of a pin 22 and the other end secured to the draw-head by means of a pin 23, passing through an opening 24, one of which is formed in each 5 draw-head. In case both knuckles become injured the heads are connected together by means of the long coupling-bar 21, as shown in Fig. 3, the bar being held by means of two pins 23, passing through the openings 24, above 10 referred to. By using solid bars having openings in their ends when the draw-heads are rigidly connected together no play is allowed between them, as would be the case if ordinary coupling-links were used.

15 I am aware that it has heretofore been proposed to provide the draw-head of a car with stops arranged in pairs above and below the head and engaging directly with the head or knuckle of the opposite car. I am also aware 20 that it has been proposed to provide the draw-head of a car with stops pivotally mounted on the knuckle-pin. I am also aware that it has been proposed to provide the knuckle of a draw-head with a pair of stops formed 25 integral with the pivoted end of the knuckle and engaging directly with the draw-head or knuckle of the opposite car. I am also aware that it has been proposed to couple two draw-heads of the Janney type together by means 30 of ordinary coupling-links after the knuckles have become injured, and hence I do not claim such constructions.

Having fully described my invention, what I claim as new, and desire to secure by Letters 35 Patent of the United States, is—

1. In a coupling device, the combination

with a draw-head and pivoted knuckle, of a forwardly-projecting stop rigidly carried by the upper face of said knuckle intermediate of its length, said stop being elevated above 40 the upper face of the coupler, whereby vertical play is permitted between said coupler and a second coupler with which it co-operates.

2. In a coupling device, the combination 45 with a draw-head and pivoted knuckle, of a forwardly - projecting stop formed integral with the upper face of said knuckle intermediate of its length, said stop being elevated above the upper face of the coupler, whereby vertical play is permitted between said coupler and a second coupler with which it co-operates.

3. The combination with a pair of co-operating coupling devices, each provided with 55 an opening for the passage of a coupling-pin, of a pivoted knuckle for each of said coupling devices, each of said knuckles also being provided with an opening for the passage of a coupling-pin, a pair of coupling-bars of unequal length, each provided with a pair of openings, and coupling-pins for rigidly connecting said coupling devices by said coupling-bars when one or both of said knuckles 60 are disabled.

In testimony whereof I have hereunto set my hand and affixed my seal in the presence of the two subscribing witnesses.

DAVID P. MORAN. [L. S.]
